Primary Examiner — Ricky Pham

(57) **CLAIM**

The ornamental design for a cutting board with a heart-shaped cut-out handle, as shown and described.

DESCRIPTION

FIG. 1 is a top plan view of the cutting board with a heart-shaped cut-out handle;

FIG. 2 is an isometric view of the cutting board with a heart-shaped cut-out handle; and,

FIG. 3 is a top plan view of a person's hand holding the cutting board with a heart-shaped cut-out handle.

The broken lines shown in the drawings are for illustrative purposes only and form no part of the claimed design.
